UNITED STATES PATENT OFFICE.

JOHN DOVE ISAACS, OF OAKLAND, AND JAMES BUCKNER SPEED, OF BERKELEY, CALIFORNIA, ASSIGNORS TO RIFLED PIPE COMPANY, OF SAN FRANCISCO, CALIFORNIA, A CORPORATION OF CALIFORNIA.

FLUID-NOZZLE.

No. 835,619.

Specification of Letters Patent.

Patented Nov. 13, 1906.

Application filed June 23, 1905. Serial No. 266,575.

To all whom it may concern:

Be it known that we, JOHN DOVE ISAACS, a resident of Oakland, and JAMES BUCKNER SPEED, a resident of Berkeley, Alameda county, State of California, citizens of the United States, have invented certain new and useful Improvements in Fluid-Nozzles; and we hereby declare the following to be a full, clear, and exact description of the same.

10 Our invention relates to the class of nozzles and is especially applicable in connection with the piping of a fluid according to the art or method disclosed in Letters Patent of the United States, No. 759,374, granted to us 15 May 10, 1904, to which patent reference is hereby made. In this method the fluid to be piped, together with a fluid of greater specific gravity, is caused to advance through the pipe-line with a helical motion about the axis 20 of the fluid content sufficient to envelop the lighter with the heavier fluid, thereby reducing the friction on the pipe-walls.

Our present invention consists in a special nozzle which is adapted to supply the fluids 25 to the helically-rifled pipe-line which induces and maintains the required motion of the fluid content in such a manner as to give to said fluids an initial helical motion, thereby assisting in the inauguration and attainment 30 of the required motion.

Referring to the accompanying drawings, Figure 1 is a side elevation of the apparatus for carrying out the method, the pipe-line A being broken to show the discharge end of 35 the nozzle. Fig. 2 is an enlarged cross-section on the line x x , looking back toward the nozzle.

40 A is the pipe-line, having on its interior a helically-directed obstruction a of suitable form.

B is the pump by which the lighter fluid—such, for example, as oil—is supplied to the pipe-line, and C is the pump by which the heavier fluid, such as water, is supplied to 45 said line. The pipe b from the pump B communicates with the rear end of the nozzle-pipe D, the discharge end d of which projects, as shown, into the pipe-line. Within

this discharge end d are seated the helically-directed flanges d' , which impart an initial 50 helical motion to the oil passing through the nozzle.

The pipe c from the water-pump C communicates with the pipe-line around the nozzle end. Between said pipe-line and the exterior of the nozzle end are seated helically-directed flanges E, which give the initial helical motion to the water as it advances in the pipe-line to join the oil.

Having thus described our invention, what 60 we claim as new, and desire to secure by Letters Patent, is—

1. A nozzle, the wall of which being fashioned to form upon both its interior and exterior surface helically-directed flanges, in 65 combination with a surrounding pipe extending therebeyond and having upon the interior wall of its extended portion similarly-arranged flanges.

2. In an apparatus for piping a fluid ac- 70 cording to the method stated, and in combination with a helically-rifled pipe-line, a nozzle therewithin provided with means for delivering the fluids to the rifled pipe-line with an initial helical motion.

3. In an apparatus for piping a fluid ac- 75 cording to the method stated, and in combination with a helically-rifled pipe-line, a nozzle provided with helically-directed flanges for delivering the fluids to the rifled pipe- 80 line with an initial helical motion.

4. In an apparatus for piping a fluid ac- 85 cording to the method stated, and in combination with a helically-rifled pipe-line, a nozzle for delivering two fluids with an initial helical motion, to the pipe-line, consisting of a pipe fitted to the pipe-line and provided 90 interiorly with helically-directed flanges for delivering one fluid, and exteriorly with helically-directed flanges for delivering the other fluid.

5. In an apparatus for piping a fluid ac- 95 cording to the method stated, the combination of a helically-rifled pipe-line, a nozzle for delivering two fluids with an initial helical motion to the pipe-line, consisting of a

pipe fitted to the pipe-line and provided interiorly with helically-directed flanges, and also with helically-directed flanges exteriorly between it and the walls of the pipe-line, a connection of the inserted pipe with the source of one of the fluids and a connection with the pipe-line back of the exterior nozzle-flanges with the source of the other fluid.

In witness whereof we have hereunto set our hands.

JOHN DOVE ISAACS.
JAMES BUCKNER SPEED.
